16 Claims. (Cl. 121-40)

1

This invention relates to a pneumatically controlled hydraulic prop for supporting heavy loads and of the type comprising a hydraulic cylinder-and-ram assembly which extends and contracts in the operation of the prop.

A prop according to the invention comprises a hydraulic cylinder-and-ram assembly the components of which are associated with a pneumatic control device operated by compressed air, and a contraction-checking valve (herein called a "check-valve") in the hydraulic ram for locking inside the hydraulic cylinder the hydraulic fluid that fills it, the check valve being operable under the pressure of the pneumatic fluid to pass hydraulic fluid from the interior of one to the interior of the other of the components of the hydraulic assembly in the extension and contraction of the prop.

The prop may have provision for operation of the check valve by a component of the pneumatic device in order to pass hydraulic fluid from the hydraulic cylinder to the interior of the hydraulic ram during contraction of the prop.

The prop may be fitted with an auxiliary valve contrived to open in advance of the check valve in order to pass hydraulic fluid from the one hydraulic component to the other at a greatly restricted rate at the start of contraction of the prop.

The prop may have a relief valve adapted to open when the pressure in the hydraulic cylinder exceeds a safety limit and to discharge hydraulic fluid from said cylinder to the interior of the hydraulic ram.

An example of a hydraulic prop embodying the invention is shown in the accompanying drawings, in which Fig. 1 is a vertical section showing the prop in its normally extended state, and Fig. 2 is a vertical section showing the prop as it starts to contract.

In the drawings, the cylinder of the hydraulic cylinder-and-ram assembly is denoted by 1 and the ram is denoted by 2. In the example the hydraulic cylinder 1 is the lower component of the prop and the hydraulic ram 2 is the upper component.

The ram 2 is a hollow body with a roof-engaging cap 3. The body of the ram is totally enclosed except that it has a central gland 4, the check valve 5, and a relief valve 6 in its bottom 7, and there is an opening 8 in its top 9, into which an indicator in the form of a whistle 10 is fitted. This whistle is so made that if air is blown into it through the opening 8, the whistle will sound. In use of the prop, the space S en-

closed by the cylinder 1 and ram 2 is completely filled and the ram 2 is partly filled with hydraulic fluid, namely oil 31.

The pneumatic control device includes a rigidly stationary ram comprising a composite rod that consists of inner and outer co-axial tubes 11 and 12 secured to the hydraulic cylinder base 1A and a piston 13 at the top of both tubes. The outer tube 12 has a sealing sliding fit through the gland 4 in the hydraulic-ram bottom 7. The pneumatic control device also includes a cylinder 14, which contains the piston 13 and is located inside the hydraulic ram 2. The lower end of the pneumatic cylinder 14 is formed as a neck 14A slidable on the outer tube 12, but is otherwise closed, whereas the upper end of the cylinder 14 opens through ports 15 into the inside of the hydraulic ram 2. The pneumatic cylinder 14 is movable not only with the hydraulic ram 2 but to a small extent relatively to it. The inner and outer tubes 11 and 12 constitute separate air conduits 16 and 11. The central conduit 16 opens through the pneumatic piston 13 to the open upper end of the pneumatic cylinder 14, and the outer annular conduit 11 opens below the pneumatic piston 13 into the closed lower end of the pneumatic cylinder 14. Normally, the pneumatic cylinder 14 comes against the hydraulic-ram top, and the whistle 10 is kept closed by a part 18 on the pneumatic-cylinder top.

The check valve 5 is a non-return valve, which normally is kept tightly closed against its seat 19 by a spring 20. The valve 5 is associated with a force-magnifying lever 21 that is fulcrummed at 22 on the bottom 7 of the hydraulic ram 2 and can be depressed open by the pneumatic cylinder 14.

The relief valve 6 also is non-return and spring-pressed, the valve having a spring 23 adapted to open it from its seat 24 when the pressure in the hydraulic cylinder 1 exceeds a limit; in the example this limit is one ton per square inch, corresponding to a load on the prop of about one hundred and fifty tons.

The check valve 5 is fitted with a normally closed, spring-pressed auxiliary non-return valve 24, which can be opened by the pneumatic cylinder 14. This auxiliary valve 24 controls a small opening 25 leading through the check valve by way of ports 26 and an annular passage 27 to the inside of the ram 2.

The pneumatic device 11 to 14 is supplied from an external source of compressed air through any appropriate control valve (not shown) in communication with the two air conduits 16 and

17 by way of ducts 28 and 29 respectively extending through the base 1A of the cylinder 1 to the exterior of the prop.

In use of the prop, it must first be extended to engage tightly between the floor A and roof B of a mine. To do this, a worker manipulates the control valve so that compressed air passes through the central conduit 16 and the upper end of the pneumatic cylinder 14 into the hydraulic ram 2 and, pressing upon the hydraulic fluid 31 therein, forces the check valve 5 to open against the yielding resistance of its spring 20 and forces oil from the ram into the space S within the hydraulic cylinder 1. Thus, the ram 2 is forced to rise and its cap 3 engages the roof, exercising an initial holding pressure which may be of the order of thirteen tons. As soon as the ram 2 comes to rest against the roof, the oil flow through the check valve 5 ceases, so that the check valve closes under the influence of its spring and locks inside the hydraulic cylinder 1 the oil filling it. The pressure inside the hydraulic cylinder may now increase to any extent (say, under subsidence of the mine roof B) as far as the limit for which the relief valve is set, without any contraction whatsoever of the prop.

When the prop is being extended in the manner described, if the operation should be continued beyond the full-extension limit (for instance, there might be a looseness or opening in the roof) a warning is given by the whistle 10. At the limit mentioned, the pneumatic cylinder 14 (rising with the hydraulic ram 2) is stopped by meeting the always stationary pneumatic piston 13, so that the still rising hydraulic-ram top 9 leaves the pneumatic-cylinder top part 18 and uncovers the whistle 10, which is then blown by compressed air from the pneumatic cylinder.

In the event that the prop is to be contracted, say for removal, a worker manipulates the control valve so that compressed air passes through the outer conduit 17 into the pneumatic cylinder below the piston 13. Such air forces down the pneumatic cylinder, which initially strikes and opens the auxiliary non-return valve 24, so that the oil escapes from the space S within the hydraulic cylinder 1 at a very low rate. Thus, the prop starts to contract very slowly under its roof load. After a very short descent of the pneumatic cylinder 14, as Fig. 2 shows, this cylinder makes contact with the lever 21, which as the descent continues opens the check valve 5, so that oil may now pass at a higher rate from the hydraulic cylinder 1, and the speed of contraction of the prop correspondingly increases. When the roof load ceases to depress the hydraulic ram 2, the pneumatic cylinder 14 in its continued descent (relatively to the now stationary hydraulic ram) engages the hydraulic-ram bottom 7 and forces the ram to descend until either the compressed air is cut off by the worker or the ram is fully contracted.

It will be manifest that, in regard to oil supply, the improved prop is a self-contained unit. One advantage of this is that each time the prop is dismantled for testing and overhaul (say once or perhaps twice per year) it can be given a supply of truly clean oil, and this is an essential to "drop tightness"; that is to say, complete sealing against escape of oil from inside the hydraulic cylinder so that the prop does not contract to any measurable extent throughout each period of use.

Another advantage of the improved prop is that, once it is set in position, it is independent

4
of external power and therefore of difficulties due to failure of power supply, burst pipes, leaky connections and valves, and broken fittings.

Another advantage is that the hydraulic valves and working parts and the hydraulic connections are all housed in the interior of the prop, where they are safe from damage and dirt.

Seeing that the operation of the prop is effected by pneumatic power, there is also the advantage that provision of costly high-pressure hydraulic plant is avoided, notwithstanding that the improved prop is itself a high-pressure hydraulic appliance. Moreover, quite a simple pneumatic power plant will suffice for a large installation of props.

By virtue of the auxiliary valve 24, it is ensured that when the prop is being contracted there is an initial period, which need only be of brief duration, during which the pressure on the roof B is reduced gradually. Once that period has passed, the prop is rapidly contracted. The arrangement is such that this sequence of operations occurs automatically, being out of the control of the operator.

I claim:

1. An extensible and contractible prop comprising a hydraulic cylinder-and-ram assembly the main components of which are a cylinder and a hollow ram in telescopic relation, a space enclosed by the cylinder and ram components being filled with a hydraulic fluid, a normally closed check valve in the ram component, said valve being adapted to open in the direction towards said hydraulic-fluid-filled space and when opened forming a passage for the hydraulic fluid from one of said components to the other, a pneumatic control device mounted inside one of said components and co-operating with said check valve, means for conducting pneumatic fluid into said device to actuate it so that it forces the check valve to open and release hydraulic fluid from the hydraulic-fluid-filled space, the control device in this event engaging the component containing it and thus forcing the prop to contract, and an outlet for the pneumatic fluid from said device into the interior of one of said components to apply pneumatic pressure to hydraulic fluid in this one of the components in order to cause this fluid to force said valve to open so that the hydraulic fluid flowing through the valve into said space will force the prop to extend.

2. An extensible and contractible prop according to claim 1 including also an auxiliary non-return valve carried by the ram and arranged to co-operate with said pneumatic control device, being engageable by said device to open in advance of the check valve and pass the hydraulic fluid from one of said components to the other at a restricted rate.

3. An extensible and contractible prop according to claim 2 in which said check valve has a through passage and said auxiliary non-return valve is mounted in said check valve and controls said passage.

4. An extensible and contractible prop according to claim 1 including also a lever fulcrummed on the hollow ram and interposed between the pneumatic control device and the check valve, said lever serving to magnify motion transmitted through it from said device to said valve.

5. An extensible and contractible prop comprising a hydraulic cylinder-and-ram assembly the main components of which are a cylinder and a hollow ram in telescopic relation, a space

enclosed by the cylinder and ram components being filled with a hydraulic fluid, a normally closed check valve in the ram component, said valve being adapted to open in the direction towards said hydraulic-fluid-filled space and when opened forming a passage for the hydraulic fluid from one of said components to the other, a pneumatic control device consisting of a telescopically related piston part and a double-ended cylinder part, one of said parts being attached to the hydraulic cylinder component and the other of said parts co-operating with said check valve and with the ram component, means for conducting pneumatic fluid into one end of said pneumatic cylinder part to actuate the device so that its cylinder part forces the check valve to open and release hydraulic fluid from the hydraulic-fluid-filled space, the cylinder part in this event engaging the ram component and thus forcing the prop to contract, and an outlet for the pneumatic fluid from the other end of said device into the interior of one of said components to apply pneumatic pressure to hydraulic fluid in this one of the components in order to cause this fluid to force said valve to open so that the hydraulic fluid flowing through the valve into said space will force the prop to extend.

6. An extensible and contractible prop according to claim 5 including tubular conduits securing one of said pneumatic parts to said hydraulic cylinder component and serving to pass the pneumatic fluid to the opposite ends of the pneumatic cylinder part alternatively.

7. An extensible and contractible prop comprising a hydraulic cylinder and a hollow ram in telescopic relation, a space enclosed by said cylinder and ram being filled with a hydraulic fluid, a check valve in the ram, said valve being adapted to open in the direction towards said hydraulic-fluid-filled space and when opened forming a two-way passage for the hydraulic fluid between said cylinder and ram, a spring normally holding said check valve closed, a pneumatic control device extending inside said ram, said device co-operating with said check valve and with said ram, means securing said device to said cylinder and for conducting pneumatic fluid into said device to actuate it so that it opens the check valve and engages the ram, thus releasing hydraulic fluid from the hydraulic-fluid-filled space and forcing the prop to contract, and a conduit for passing the pneumatic fluid through said device into the interior of the ram to apply pneumatic pressure to hydraulic fluid inside the ram in order to cause this fluid to force said valve to open so that the hydraulic fluid flowing through the valve into said space will force the prop to extend.

8. An extensible and contractible prop according to claim 7 including also an auxiliary non-return valve carried by the ram and arranged to co-operate with said pneumatic control device, being engageable by said device to open in advance of the check valve and pass the hydraulic fluid from the ram into the hydraulic cylinder at a restricted rate.

9. An extensible and contractible prop according to claim 8 in which said check valve has a through passage and said auxiliary non-return valve is mounted in said check valve and controls said passage.

10. An extensible and contractible prop according to claim 7 including also a lever fulcrummed on the hollow ram and interposed be-

tween the pneumatic control device and the check valve, said lever serving to magnify motion transmitted through it from said device to said valve.

11. An extensible and contractible prop comprising a hydraulic cylinder and a hollow ram in telescopic relation, a space enclosed by said cylinder and ram being filled with a hydraulic fluid, a check valve in the ram, said valve being adapted to open in the direction towards said hydraulic-fluid-filled space and when opened forming a two-way passage for the hydraulic fluid between said cylinder and ram, a spring normally holding said check valve closed, a pneumatic control device consisting of a telescopically related piston part and cylinder part, both of said parts being located inside the ram and a movable one of them co-operating with said check valve and with said ram, means securing the other of said parts stationarily to said hydraulic cylinder and for conducting pneumatic fluid into said cylinder part to actuate said device so that its movable part can open the check valve and engage the ram in order to release hydraulic fluid from the hydraulic-fluid-filled space and force the prop to contract, and a conduit for passing the pneumatic fluid through said device into the interior of the ram to apply pneumatic pressure to hydraulic fluid inside the ram in order to cause this fluid to force said valve to open so that the hydraulic fluid flowing through the valve into said space will force the prop to extend.

12. An extensible prop according to claim 11, including also an auxiliary non-return valve carried by the ram and arranged to co-operate with said pneumatic control device, being engageable by said device to open in advance of the check valve and pass the hydraulic fluid from the ram into the hydraulic cylinder at a restricted rate.

13. An extensible prop according to claim 12, in which said check valve has a through passage and said auxiliary non-return valve is mounted in said check valve and controls said passage.

14. An extensible and contractible prop according to claim 11 including also a lever fulcrummed on the ram and interposed between the movable pneumatic cylinder part and the check valve, said lever serving to magnify motion transmitted through it from said part to said valve.

15. An extensible and contractible prop comprising an upper hydraulic ram and a lower hollow cylinder in telescopic relation, the lower portion of the cylinder being filled with a hydraulic fluid, a base portion of said ram partitioning the interiors of the cylinder and ram, a normally closed check valve in said base portion, said valve being adapted to open downwards and when opened passing the hydraulic fluid from one of said interiors to the other, a pneumatic control device consisting of a piston stationarily secured to the hydraulic cylinder and a pneumatic cylinder movably located inside the ram and containing said piston, said pneumatic cylinder co-operating with said check valve and said base portion, means securing said piston stationarily to the hydraulic cylinder and extending through the base portion in sliding relation therewith, said securing means serving to conduct pneumatic fluid into said pneumatic cylinder to actuate it so that it opens said check valve, thus releasing the hydraulic fluid from the hydraulic cylinder interior, and engages said

ram, thus forcing the prop to contract, and a conduit combined with said securing means for passing the pneumatic fluid through said device to the interior of the ram to apply pneumatic pressure to hydraulic fluid in this one of the components in order to cause this fluid to force said valve to open and the prop to extend.

16. An extensible and contractible prop according to claim 15 including also an auxiliary non-return valve carried by the ram and arranged to co-operate with said pneumatic control device, being engageable by said device to open in advance of the check valve and pass the

hydraulic fluid from one of said interiors to the other at a restricted rate.

JOHN MAURICE TOWLER.
